UNITED STATES PATENT OFFICE

2,006,975

SUPERVISORY INDICATION OF CARRIER
CURRENT TRANSMITTERJohn L. Woodworth, Schenectady, N. Y., assignor
to General Electric Company, a corporation of
New York

Application October 21, 1930, Serial No. 490,239

4 Claims. (Cl. 177—311)

My invention relates to signal systems and more particularly to answer back means therefore.

In application Serial No. 463,199, filed June 5 23, 1930, U. S. Patent No. 1,869,185, granted July 26, 1932, to Henry R. Crago for Remote control systems, and which is assigned to the same assignee as my present application, is shown a system, adapted more particularly for 10 remote control purposes, whereby high frequency impulses of different durations may be transmitted over each of a plurality of outgoing circuits. The impulses may be utilized to operate remote selectors for control of street lamps, or 15 the like and for any desired purpose whatever. Thus, for example, a high frequency impulse of a certain duration may be transmitted to cause the street lights to be turned "on" and one of longer duration to cause the street lights 20 to be turned "off". The transmitter may be selectively controlled to transmit said signal impulses of either duration automatically over each of the outgoing circuits in succession, thereby to control all of the remote control 25 units, which are associated with the different outgoing circuits, to cause them to be turned either "on" or "off" in accordance with the duration of the impulses transmitted.

It is frequently desirable to control transmitters of this type from a remote point through the remote or supervisory control equipment which may be available at the point where the transmitter is located. In connection with such remote control of the transmitter it is necessary 35 to provide means whereby a satisfactory supervisory indication, or answer back, is produced at the point from which the control of the transmitter is effected.

An object of my present invention is to provide 40 an answer back mechanism satisfactory for use in connection with a transmitter of the type indicated.

Another object of the invention is to provide means whereby an answer back signal is produced only when the transmitter has functioned 45 to transmit the proper signal over all of the outgoing circuits and whereby no answer back signal is produced if, as through faulty operation of the equipment, the desired signal is transmitted only over a portion of the outgoing circuits.

The novel features which I believe to be 50 characteristic of my invention are set forth with particularity in the appended claims. My 55 invention, itself, however, both as to its organi-

zation and method of operation together with further objects and advantages thereof may best be understood by reference to the following description taken in connection with the accompanying drawing, in which Fig. 1 represents an embodiment of my invention and Fig. 2 represents a detail thereof.

Referring to the drawing, I have shown at 1 a rectangle representing a transmitter of the type indicated in the above mentioned application. This transmitter is adapted for remote control by means of a pair of relays 2 and 3 which may be operated from a remote point through a supervisory control equipment, the remote station equipment of which is indicated 5 by the rectangle 4. This equipment may be associated with a dispatcher's station equipment by means of conductors 5 over which the remote control and supervisory impulses are transmitted. The supervisory control equipment may be of any suitable type, such as, for example, the type disclosed in U. S. Patent 1,844,648 granted February 9, 1932, to T. S. Farley et al.

At 6 I have shown a polyphase power distribution system which may be utilized to distribute power to a plurality of remote apparatus units such as street lamps which are to be remotely controlled by the transmitter 1 through the agency of carrier current transmitted over 25 the power distribution system. The different street lamps of course are supplied with energy from the different phases of the power distribution system and accordingly, in effecting remote control, it is necessary that the carrier current 30 be transmitted over each of the different phases of the power system. The transmitter, therefore, by reason of considerations of economy, is adapted when placed in operation automatically 35 to transmit the desired signal impulses 40 over the different phases of the power system in succession.

Thus, for example, if the dispatcher at a remote point desires to turn the street lamps on he will operate relay 2 through the supervisory 45 control equipment 4 and thereby cause the transmitter 1 to be placed in operation. The transmitter includes a high frequency generator 7, which is operated by a motor 8, and which may be connected to each of the different phases of 50 the power system by means of switches 9, 10 and 11. Any suitable means for causing the successive actuation of switches 9, 10, and 11, may be 55 employed, such means being conventionally represented by the motor 29, which may be ener-

gized in response to relay 2 to operate a contact member 38 over a bank of contacts to which the windings of switches 9, 10, and 11 are connected. Thus, after operation of relay 2 the motor 8 becomes energized to drive the generator 7, and motor 29 becomes energized to operate the contact member 38 over its bank of contacts. The switches 9, 10, and 11 are then closed in succession, each of the switches being closed for a proper interval sufficient to cause the street lamps associated with the respective phase of the power system to be turned "on." Thus after closure of each switch it is opened and the next switch closed. When the last switch 11 has been closed for its proper interval, the operation of the transmitter is interrupted. The same operation occurs when relay 3 is operated but switches 9, 10 and 11 are closed each for a longer interval thereby to cause the street lights to be turned "off."

It will of course be understood that the transmitter 1 may be of any desired type and that the elements indicated in the rectangle representing this transmitter are shown only for the purpose of indicating conventionally, and as simply as possible, on the drawing, the general nature of apparatus which may be employed, a more preferred form of apparatus being fully explained in Patent 1,869,185 above referred to.

My present invention relates to means whereby a proper answer back signal may be transmitted through the supervisory equipment 4 only when the desired remote control or signal impulses have been transmitted over all of the different outgoing circuits or phases of the power system and whereby upon failure of the equipment to transmit the desired signal impulse over any one or more of the different outgoing circuits no answer back indication is produced.

To this end a number of carrier current receivers 12, 13 and 14 are provided, these receivers being associated with the different outgoing circuits or phases of the power system. These receivers may be of any suitable construction adapted selectively to respond to the transmitted signals. Thus for example these receivers may be of the type shown in my co-pending application, Serial No. 443,909, filed April 12, 1930, U. S. Patent No. 1,816,755, granted July 28, 1931, for selective control systems, a portion of which is shown in Fig. 2 of the drawing. Each of these receivers comprises a bimetallic conducting member 15 which may be supplied with an energizing current through means not shown in response to received carrier current from the corresponding phase of the power system. The receiver includes an armature 16 which is pivoted at one end 17 and the opposite end of which rests on the upper end of the bimetallic member 15. To the armature 16 is attached a contact carrying member 18 which reciprocates between the stationary contacts 19 and 20. Thus when the armature is in its upper position the contact 18 engages the contact 19. When, due to heating of the bimetallic strip 15, it deflects to the left, it permits the armature 16 to be attracted by the horseshoe magnet 21 and causes the contact 18 to be operated to its lower position and into engagement with stationary contact 20. Thus, when carrier current is received for an interval having the duration necessary to cause the street lamps to be turned on, the bimetallic member 15 is energized and deflects just sufficiently to release the armature 16 and permit it to be attracted to its lower position.

Cooperating with the thermostat 15 and the contact carrying member 18 is a small bell lever member 22 having an arm 23 which normally projects downward and to the left of the bimetallic strip 15 and a second arm 24 which projects to the right between the armature 16 and the contact carrying member 18, this lever being pivoted at a central point in such a way that it is freely suspended in the position shown in the drawing.

When the long carrier impulse which is utilized to turn the street lamps off is received the bimetallic strip 15 is deflected proportionately further to the left and accordingly it engages the arm 23 of the bell lever and causes it to swing clockwise about its pivot. When the bimetallic strip has about reached the extent of its deflection it passes the lever 23 which falls behind it. Then, when the carrier impulse is interrupted the bimetallic strip tends to cool and to return to its initial position. As it does so, it engages the opposite side of the lever 23 and rocks the lever about its pivot in a counter clockwise direction thereby forcing the arm 24 upward until it engages the contact carrying member 18 and forms it into its upper position. As it does so the bimetallic strip 15 slips past the lever 23 and under the armature 16 thereby holding the armature 16 in its upper position.

Thus each of the receivers 12, 13, and 14 of Fig. 1 have two stationary contacts 19 and 20 and an armature reciprocal therebetween. All of the contacts 20 are connected together and to one side of a resistance 25 and similarly all the contacts 19 are connected together and to the opposite side of resistance 25. A suitable source of potential 26, such as a battery, is connected between the midpoint on resistance 25 and all of the armatures 18. In parallel with resistance 25 is connected the winding of polarized answer back relay 27.

Thus when all of the armatures 18 engage the stationary contacts 20, the battery 26 is connected across the lower portion of resistance 25 and the polarized relay is energized in such a direction as to actuate its armature toward the right. When all the armatures engage their respective contacts 19 the source of potential 26 is connected across the upper portion of resistance 25 and the relay 27 is energized in the opposite direction and accordingly actuates its armature to the left. The supervisory equipment is of course arranged to transmit signals in accordance with the position of the armature of the answer back relay 27.

Thus if the transmitter 1 functions properly and transmits a signal over each of the different outgoing circuits of proper duration to turn the street lamps either "on" or "off" a corresponding answer back indication will be transmitted to the dispatcher's station. If we assume, however, that in the operation of the transmitter a fault occurs such, for example, as switch 11, failing to respond whereas switches 9 and 10 operate properly, it will be observed that armature 18 of receiver 12 will then be in engagement with its contact 19 whereas armature 18 of receivers 13 and 14 will engage their contacts 20. The winding of relay 27 is then short-circuited and the relay deenergized. The relay will therefore remain in the position at which it last operated and accordingly no return signal is given. Thus the operator is informed that some fault has occurred in the operation of the equipment at the remote station.

While I have particularly mentioned impulses of long and short duration and have shown in part a selective receiver to respond to such impulses, it will of course be understood that I do not wish to be limited thereto since my invention is equally operable to systems utilizing any other type of selective signals, it being necessary only to utilize a different and well known type of receiver in connection therewith.

Thus while I have shown a particular embodiment of my invention, it will be understood that this embodiment is capable of different modifications and that I contemplate by the appended claims to cover any modifications which fall within the true spirit and scope of my invention.

What I claim as new and desire to secure by Letters Patent of the United States is:

1. In combination, a plurality of circuits, means for automatically applying predetermined signals to each of said circuits, an answer back signal device, and means selectively responsive to said predetermined signals applied to each of said circuits to operate said answer back signal device when the same predetermined signal has been applied to all of said circuits, said means including means for normally preventing operation of said answer back device upon failure of said predetermined signal to be applied to any one of said circuits.

2. In combination, a transmitter having a plurality of output circuits, means for controlling said transmitter from a remote point to cause it selectively to apply predetermined signals to each of said output circuits in succession, and answer back signal means for transmitting an indication to said remote point, said

last means including means for transmitting said indication only when the same predetermined signals have been applied to all of said circuits.

3. In combination, a plurality of signal circuits, a transmitter arranged to transmit different predetermined signals, means for selectively controlling said transmitter to cause it to apply any of said signals to each of said circuits, selective means responsive to said signals connected to each of said circuits, and means controlled by said last means for transmitting an indication in accordance with the signal transmitted, said last means including means for normally preventing the transmission of said indication except when the same signal has been applied to all of said circuits.

4. In combination, a plurality of signal circuits, a transmitter arranged to transmit either of two different signals, each of said signals being transmitted over each of said circuits, a polarized answer back relay having a resistance connected in shunt with the winding thereof, a source of potential and means connected to each of said signal circuits selectively to connect said source of potential between the midpoint on said resistance and one of the ends thereof dependent upon the signal transmitted, all of said means being arranged in response to the same signal to connect said source between the midpoint and the same end of said resistance whereby said relay is energized with current having polarity determined in accordance with the signal transmitted and is deenergized in response to failure of either of said signals to be applied to all of said circuits.

JOHN L. WOODWORTH.
